HAIR CURLING APPARATUS

Carl Henry Bongartz, Twickenham, England, assignor of two-fifths to Stanley Marcell, Claygate, England

Application February 12, 1934, Serial No. 710,906
In Great Britain December 12, 1932

6 Claims. (Cl. 132—36)

This invention relates to apparatus for use in processes of permanently curling and waving the hair wherein tresses of hair are wound upon curlers or mandrels and subjected to heat treatment in steaming tubes and the like, and has for its object to improve the construction and arrangement of the curlers and steaming tubes so as to enable such hair curling and waving processes to be efficiently and rapidly effected with the minimum skill and labour.

According to this invention hair curling and waving apparatus comprises a steaming tube or cylinder furnished with bearings between which a curler can be detachably and rotatably mounted, one of such bearings being rotatable through a releasable one-way clutch operable from the exterior of the tube or cylinder so that the curler or mandrel can be rotated in one direction in the tube or cylinder for the purpose of winding a tress of hair thereon, said clutch mechanism being releasable so as to enable the curler to rotate in the reverse direction for unwinding the said hair tress therefrom, while the steaming tube is adapted to be closed steam tight about the ligament end of a hair tress coiled upon the rotatable curler or mandrel so as to enable such hair tress to be treated with steam supplied to or generated in the interior of the steaming tube or cylinder by known types of heating devices.

The invention is fully described and ascertained in the following description and appended claims and illustrated in the accompanying drawings, wherein similar references indicate like parts.

Fig. 1 is a longitudinal sectional view on the line I—I Fig. 2 showing one construction of steaming tube and rotatable curler in accordance with the present invention adapted for use in connection with an external source of heat.

Fig. 2 is a cross section on the line II—II Fig. 1 showing the steaming tube closed;

Fig. 3 is a similar view showing the steaming tube open;

Fig. 4 is a cross section on the line IV—IV Fig. 1 showing a releasable ratchet and detent mechanism presently referred to;

Fig. 5 is an external plan view of the steaming tube shown in Fig. 1;

Fig. 6 is a detail sectional view drawn to a larger scale showing one construction for clamping a tress of hair steam tight between the steaming tube and its closure;

Fig. 7 is a perspective view, and Fig. 8 a cross section illustrating another construction for

clamping a tress of hair steam tight between the steaming tube and its closure;

Fig. 9 is a perspective view of the steaming tube illustrated at Figs. 1—6 inclusive;

Fig. 10 is a perspective view showing the liner removed from the steaming tube shown in Figs. 1, 7 and 8;

Fig. 11 is a detail view of a modified arrangement of the steam outlet nozzle shown in Fig. 1;

Fig. 12 is a cross section illustrating a modified construction of steaming tube adapted for use with a known type of removable autogenous chemical heating device;

Fig. 13 is a plan view with parts broken away;

Fig. 14 a cross section on the line XIV—XIV Fig. 13, and Fig. 15 a perspective view, and Fig. 16 a detail view illustrating a modified construction of steaming tube presently referred to;

Figs. 17 and 18 are diagrammatic plan views illustrating the manner of use of the improved hair curling apparatus in accordance with the present invention.

In the construction illustrated at Figs. 1—5 the steaming tube 1 comprises an outer tube of heat resisting and insulating composition or material such as fibre, bakelite or the like, which tube is furnished with a removable metal liner 2 and is cut away intermediate its ends 3 and 4 so as to form an aperture 5 which is furnished with a hinged cover 6 shaped so that when closed it completes the tube 1 and forms a steam tight closure for the aperture 5.

The cover 6 is attached by an internal hinge 7 to one longitudinal edge of the aperture 5, while its closing edge 6b is adapted to form a steam tight joint with the root end of the coiled hair tress as presently described.

The metal liner 2 is of sufficient length to extend into the ends 3 and 4 of the outer tube 1 and is similarly cut away between its ends 3a and 4a (see Fig. 10) so as to form an opening 4b which registers with the opening 4a in the outer tube. Such liner is furnished with a sliding semi-circular cover 6a arranged so that the same can be rotated in the fixed section of the liner to give access to the interior thereof, while projections 6x are formed on the cover 6a to facilitate manipulation of the same.

The ends 3a and 4a of the tubular liner make a sliding fit in the ends 3 and 4 of the outer tube and are internally screw threaded as indicated at 7a so as to engage counterpart threads on the end plugs 8 and 12 which are adapted to form closures for the open ends 3 and 4 of the outer tube while also serving to secure the liner 2 in 110

- position therein. Such plugs may be made of metal or of the same material as the outer tube 1 and are furnished with bearings for carrying the curler rotatably mounted in the steaming tube, as presently described. 5
- For this purpose the central bore 9 is formed in the end plug 8 to form a housing for a sliding socket 10 together with a spring 11 for controlling the same. 10
- The socket 10 is retained in the bore 9 against the pressure of its controlling spring by means of an external shoulder 10a formed thereon so as to abut a counterpart internal flange 9a on the adjacent end of the bore 9. The socket 10 forms a journal bearing for one end of the curler rotatably mounted in the steaming tube as presently described, while the opposite end plug 12 of the steaming tube is furnished with a rotatable bearing which comprises a clutch member 15 adapted to engage a counterpart clutch member on the adjacent end of the curler. 20
- The end plug 12 is centrally perforated as indicated at 13 to form a journal for a spindle 14, the inner end of which carries a clutch member comprising an externally flanged socket 15 provided with an internal tooth or claw 16, while the outer end of such spindle is squared as indicated at 17 and terminates in a reduced externally threaded extension 18. 25
- A ratchet wheel 19 is secured on the squared portion of the spindle 13 and is engaged by a detent 20 pivoted at 21 to the plug 12 and controlled by a spring 22 carried by such plug as indicated at Fig. 4. The detent 21 is furnished 30 with a lever 23 that projects through a slot 24 formed in the adjacent end 4 of the steaming tube while a flanged cap 25 furnished with a central sleeve 26 is secured to the spindle 13 by a nut 27 that screws on to the threaded extension of such 35 spindle, the cap 25 being knurled as indicated at 28 and forming a finger grip for rotating the clutch spindle 13 in the direction permitted by the ratchet wheel 19 and its detent 20. 40
- The curler or waver 29 may be made in metal or other suitable material and be in the form of a curved bobbin, as indicated. Such curler is adapted to be rotatably mounted between the end plugs 8 and 12 of the steaming tube and for this purpose is furnished at one end with a cone 30 which is adapted to journal in the spring-controlled socket 10 in the end 8 while the other end of the curler is furnished with a slotted cylindrical boss adapted to operably engage the rotatable clutch comprising the socket 15 and tooth or claw 16 carried by the plug 12. 45
- The curler is mounted in the steaming tube by engaging the end 30 thereof with the spring controlled socket 10 at one end of the tube, the socket being simultaneously pressed back so that the slotted boss at the other end of the curler can be operably engaged with the rotatable clutch comprising the socket 15 and the tooth or claw 16 mounted in the end plug 12 of the tube. 50
- The curler so mounted can be rotated in the tube so as to wind a hair tress thereon by operating the external cap 25 so as to rotate the clutch in the direction permitted by the detent 20 of the ratchet wheel 19. The direction of rotation of the curler can be reversed so as to enable 55 the hair tress to be unwound by pressing the lever 23 of the detent 20 so as to disengage the same from the ratchet wheel 19. 60
- As shown, the curler is furnished with a hinged clip 31 to facilitate securing the tip of a tress 65 of hair thereto. To enable the hair tress to be coiled upon a curler the hinged door 6 of the tube 1 and also the sliding door 6a of the liner 2 are opened; the tip of the hair tress is then clipped to the curler 29 and the latter rotated by means of the cap 25 while the steaming tube 80 is moved towards the head. 85
- To prevent the steaming tube coming into contact with the head (indicated by A Fig. 3) the ends 3 and 4 thereof are respectively furnished with a projection 3c and 4c to which rubber buffers 3d and 4d are detachably secured by screws or otherwise as indicated at 4e Fig. 2. 90
- The tress of hair may be tied near the head A as indicated at a Fig. 18 so as to form the same into a tuft which is wound upon the curler 29 as indicated, or the tress of hair may be wound flat upon the curler 29 in the manner indicated at Fig. 17. After the hair tress has been wound upon the curler the sliding door 6a of the liner 2 and the hinged door 6 of the tube 1 are closed to form a steam tight joint with the ligament end of the coiled hair tress. 95
- When the hair tress is wound upon the curler in the manner indicated at Fig. 16, the closing edge 6b of the door 6 is recessed to engage a counterpart tongue 1d formed on the adjacent edge of the steaming tube 1 as indicated at Fig. 6, the edge 6b of the door and likewise the tongue 1d being furnished with rubber or other suitable packing 6e so as to make a steam tight joint 100 with the tress of hair clamped therein. 105
- Such construction may be modified by arranging a nipple 33 in the steaming tube 1 so as to enable a steam tight joint to be readily formed with the ligament end of a tress of hair wound 110 in the manner indicated at Fig. 18. For this purpose the nipple is formed in two counterpart sections disposed upon the closing edge 6b of the hinged door 6 and the adjacent edge of the steaming tube 1 as indicated at Figs. 7 and 8 115 so that when the steaming tube is closed the two sections of the nipple register with each other and may be provided with rubber or other suitable packing to form a steam tight joint with the hair tress. 120
- When the hinged door 6 is closed it is secured by means of catches 34 pivoted thereon at 35 so as to engage the catch plates 35a on the steaming tube 1, from which latter the catches 34 can be readily released by pressing the free ends 125 of the pivoted catches 34. 125
- To enable steam from an external source to be circulated through the steaming tube the latter is furnished with an inlet nozzle 36 and an outlet nozzle 37 adapted for connection to a flexible 130 inlet pipe 38 and a flexible outlet pipe in known manner. As shown, the inlet nozzle 36 is mounted in the cover 6 while an inlet perforation 39 is formed in the cover 6a of its metal liner 2. The steam escapes from the interior of the tube 135 through vent holes 40 formed in the end plug 8 to the outlet nozzle 37 which is secured in a centrally perforated cap 37a screwed or otherwise secured in the end plug 8. 140
- As shown at Fig. 11, the cap 37a is rotatably mounted upon the end plug 8 and furnished with one or more radial holes b in one or other of which the outlet nozzle 37 is detachably secured so that such nozzle may be arranged on the side of the steaming tube remote from the head. 145
- The construction illustrated at Fig. 1 may be modified by omitting the metal liner from the tube 1 as indicated at Fig. 10. 150
- In a further modification illustrated at Figs. 13, 14 and 15 the steaming tube 1 may be formed

with a sliding semi-cylindrical cover similar to that, 6a, of the liner 6 shown in the Fig. 1 construction, the closing edge of the sliding cover being adapted to engage a rebate 1b in the body 5 of the steaming tube 1 as indicated at Fig. 14, while to enable the door 6a to be secured when closed it is furnished with a releasable spring 10 detent 50 which engages ratchet teeth 51 on the adjacent edge 52 of the end 4 of the tube. Thus, when the door 6a is closed it is held by engagement of the detent 50 with the ratchet teeth 51, which detent can be readily released from the teeth to enable the door 6a to be opened.

The ends 3a and 4a of the steaming tubes are 15 closed by end plugs 8 and 12, which plugs are furnished with bearings between which a curler such as 29 can be detachably and rotatably mounted in the manner described with reference to Fig. 1.

20 To enable steam to be generated in the interior of the steaming tube instead of being supplied from an external source, the latter may be made of sufficient dimensions to accommodate a removable chemical heating pad as indicated at Fig. 10, the liquid re-agent for operating such pad being introduced through an inlet nozzle such as 36 which also serves as a vent for the steam and vapour generated in the tube.

The steaming tube is also furnished with an 30 eye 41 by means of which it can be suspended in known manner from an overhead support so that it can be readily lowered for use and raised out of the way when not required.

What I claim is:—

35 1. Hair curling and waving apparatus comprising an open ended steaming tube having closures for its ends furnished with bearings, an aperture in said tube and means for closing said aperture steam tight, a curler adapted to be detachably and 40 rotatably mounted between the bearings in the tube, one of said bearings being furnished with means operable from the exterior of the tube for rotating the curler therein in one direction, and one of said end closures being revoluble and having 45 means for causing the curler to be rotated therewith in the reverse direction.

2. Hair curling and waving apparatus as 50 claimed in claim 1, including a heating device arranged in operable combination with said steaming tube for steaming the hair tress coiled therein.

3. Hair curling and waving apparatus comprising a steaming tube, the ends of which are closed by plugs, one of which is furnished with a spring controlled slidable bearing while the other is 55 furnished with a rotatable bearing controlled by a releasable clutch and operable from the exterior of the tube, a lateral aperture in said tube, a detachable curler adapted to be mounted between said bearings and operably connected to 60 the rotatable bearing, a closure for said steaming tube adapted to make a steam tight joint with the

ligament end of a tress of hair coiled upon the curler within the tube, releasable means for securing said closure and a heating device arranged in operable combination with said steaming tube for steaming the coiled hair tress therein.

4. Hair curling and waving apparatus comprising a steaming tube having closed ends furnished with bearings, one of which is rotatably supported and operable in one direction from the exterior of the tube through a releasable ratchet and pawl mechanism, a detachable curler adapted for mounting in said bearings so as to be rotatable with the rotatable bearing, a hair clip on said curler, a lateral aperture in said steaming tube furnished with a closure adapted to form a steam tight joint with the ligament end of a tress of hair coiled on the curler within the tube, releasable means for securing said closure, and means for connecting said steaming tube to a flexible support.

5. Hair curling and waving apparatus comprising a steaming tube furnished with a removable liner, lateral apertures in said steaming tube and liner, means for closing said lateral apertures, removable end plugs each furnished with a central bearing and respectively adapted to form closures for the open ends of the steaming tube and its liner respectively, the bearing in one end plug being rotatable, and operable in one direction from the exterior of the tube through a releasable ratchet clutch, a detachable curler adapted for mounting between said bearings so as to engage and operate with the rotatable bearing, said closures being adapted to form a steam tight joint with the ligament end of a tress of hair coiled upon the curler within the steaming tube, means for suspending such steaming tube from the support and means for operably connecting said steaming tube with an external steam supply.

6. Apparatus for curling and waving the hair comprising a curler rotatably mounted within a steaming tube having closed ends and a lateral aperture through which said curler is inserted and removed, means for rotatably supporting said curler within the tube, said means being operably connected to the exterior of the tube and controlled by a releasable clutch mechanism so that the curler can be rotated in the tube in one direction for coiling and holding a hair tress thereon under tension, and released so that it can be rotated in the opposite direction for releasing said hair tress, a closure for the lateral aperture adapted to make a steam tight joint with the hair tress coiled within the tube, releasable means for securing said closure, said steaming tube being furnished with means for connecting same to a flexible support and being adapted for use with a heating device for the purpose of steaming the coiled hair tress contained therein.

CARL HENRY BONGARTZ.
